CLAIM

(21) Appl. No.: 29/126,136

The ornamental design for a rechargeable battery pack with vibrator and speaker for handheld electronic games, as shown and described.

(22) Filed: Jul. 7, 2000

DESCRIPTION

(30) Foreign Application Priority Data
Apr. 17, 2000 (HK) 0010464

FIG. 1 is a perspective view of a rechargeable battery pack with vibrator and speaker for handheld electronic games showing my new design;

(51) LOC (7) Cl. 13-02

FIG. 2 is a top plan view thereof;

(52) U.S. Cl. D13/103; D21/333

FIG. 3 is a bottom plan view thereof;

(58) Field of Search D13/103, 119;

FIG. 4 is a left side elevational view thereof;

D21/333; 429/96-100, 157, 163, 176

FIG. 5 is a right side elevational view thereof;

(56) References Cited

FIG. 6 is a rear elevational view thereof; and,

U.S. PATENT DOCUMENTS

FIG. 7 is a front elevational view thereof.
